UNITED STATES PATENT OFFICE.

JACOB REESE, OF PITTSBURG, PENNSYLVANIA.

MACHINERY FOR AND METHOD OF MANUFACTURING STEEL RAILWAY-RAILS.

SPECIFICATION forming part of Letters Patent No. 276,712, dated May 1, 1883.

Application filed November 7, 1882. (No model.)

To all whom it may concern:

Be it known that I, JACOB REESE, a citizen of the United States, residing at Pittsburg, in the county of Allegheny and State of Pennsylvania, have invented a new and useful Improvement in Machinery for and Methods of Manufacturing Railway-Rails Direct from the Ore; and I do hereby declare the following to be a full, clear, and exact description thereof, reference being had to the accompanying drawings, forming a part thereof.

In the manufacture of ingot iron and steel by the Bessemer process as at present practiced, the ores are ordinarily smelted in a blast-furnace, and the metal produced is run into pigs, which are allowed to cool, and they are then remelted in a cupola. The molten iron is then blown with an air-blast in a converter until the silicon and carbon are eliminated, or the silicon, carbon, and phosphorus are eliminated. The metal is then deoxidized, recarburized, and run into ingots. These ingots are taken while yet hot and put into a heating-furnace, and after being therein heated for an hour or more they are taken to the blooming-mill and rolled into blooms of about seven inches square. These blooms are then sheared into sections of suitable weights and again charged into a furnace, and after being heated are withdrawn and rolled into rails. By this practice the ores are heated and smelted; second, the metal is reheated and melted; third, the ingot thus produced is reheated and bloomed; fourth, the blooms are reheated and rolled into rails. As a result of such method of manufacturing rails and other merchantable shapes of iron and steel, the metal is reheated at least three times, and often more, and in such reheatings it deteriorates in quality from the absorption of deleterious matters from the fuel, wastes in quantity from oxidation and other causes, and consumes an inordinate and needless quantity of fuel.

The object of this invention is the production of steel rails and like articles direct from the ore by a continuous process or succession of interdependent steps, and in such a manner that the fuel employed in smelting and heating the metal shall be used exclusively in the blast-furnace or first stage of the process, thus

saving the fuel employed heretofore in melting the metal and reheating the ingots and blooms.

The present invention therefore consists in so combining the blast-furnace process with the converter process, and these with the steps of the several rolling and reducing processes for shaping the metal, that the waste products and by-products from the several steps shall supply the heat for carrying on the succeeding steps, thus displacing and dispensing with other fuel than that primarily employed; and, further, in such an arrangement of the working plant as shall facilitate the carrying out of said process, the limitation thereon being simply as to arrangement and not as to construction of apparatus employed, all as will herein-after more fully appear.

In the practice of this invention the ores of iron are placed in a blast-furnace, together with limestone and fuel, and smelted in the ordinary manner. When a sufficient amount of metal has accumulated in the hearth it is tapped out and conveyed to and run into a Bessemer converter. The metal is then blown with an air-blast until the silicon and carbon or the silicon carbon, and phosphorus are eliminated. The metal is then deoxidized, recarburized, and cast into ingots. The ingots are then taken from the molds and placed in an ingot-regenerator, or "soaking-chamber," as it is sometimes termed. As soon as the ingots are placed in the regenerator the lids are put on and the vessel is closed, so as to exclude the air and prevent the heat from escaping. The regenerator having been previously heated, the heat will pass from the hot walls of the regenerator into the outside of the ingots, and tend to raise their temperature, and as the inside of the ingots is in a molten state when it is taken from the mold and put into the regenerator, the molten center in solidifying will give off considerable heat, which will not only heat the outside of the ingots, but will also heat up the regenerator. After the ingots have been in the regenerator for thirty minutes, more or less, they will have acquired a uniform temperature and consistency throughout. The regenerator, if portable, may be run up to the blooming-mill and the ingots withdrawn and rolled, care being taken to close

the regenerator immediately after taking an ingot out. When the ingot is rolled into a bloom, the last end should be trimmed and the entire bloom passed immediately forward into the rail-mill, where it may be roughed and rolled into a finished rail, and then sawed into three or four rail-lengths; or, if it is preferred, the bloom, when made, may be sheared into three or four rail-lengths, and each length passed forward and rolled into single rail-lengths. In the latter case I prefer to have a double set of finishing-rolls, so that by making a four-rail ingot it may be rolled into a bloom and cut into four rail-lengths, and these taken as cut and rolled directly into rails, the first and third bloom in one pair of rolls and the second and fourth blooms in the other pair of rolls. By this method the blooms may be taken and rolled as rapidly as they can be cut, and the ingot bloomed and rolled into four-rails without reheating.

One regenerator or soaking-chamber, which I propose to use as most suitable for securing a uniform and desirable temperature in the ingots before blooming, is a continuous tube, through which the ingots are pushed from the converting-house to the blooming-mill, and the other is a portable regenerator, which may be charged in the converting-house and transported by rail to the blooming-mill. In either case the ingots are placed in the regenerator in the converting-house and taken out of it at the blooming-mill, and are thus protected from cooling while in transit.

In order to more fully explain the practice and advantages of my process of manufacturing iron and steel direct from the ore without the use of any other fuel than that employed in the blast-furnace, I shall describe a plant suitable for the purpose, having a capacity of producing six hundred tons of steel rails per day direct from the ore; but in doing so I do not limit this invention to the use of any special apparatus.

Figure 1 is a ground plan of a blast-furnace plant with four furnaces. Fig. 2 is a ground plan of the converting-house, blooming and roughing mill. Fig. 3 is a ground plan of a rail-finishing mill. Figs. 1, 2, and 3, when joined together at the lines *x x*, is a plan view of my plant for the practice of my process of manufacturing iron and steel direct from the ore without the use of any other fuel except that used in the blast-furnace.

Like letters, where they occur, refer to like parts.

In Fig. 1, *A* is a blast-furnace. *B B B* are regenerating hot-blast stoves. *C* is the waste-gas stack. *D* is the hoist; *E*, the bridge leading from the hoist to the top of the furnace. *F* is the boiler-house. *G* is the casting-house. *H* is the slag-car. *I* is the metal-car. *J* is the metal-track. *K* is the slag-track. *L* is the stock-house, with railroad-tracks *r s t u*.

Fig. 2: *a a a* are the converters. *b b* are the ingot-pits, with the ingot-molds in place. *c c* are the ladle-cranes. *d d* are the ingot-cranes.

e is the ingot-regenerator. *f* is the hopper through which the ingots are charged into the regenerator. *g* is the hydraulic ram for pushing the ingot through the regenerator. *h h* are blowing-engines for supplying blast to the blast-furnaces and the converters. *J* is the track on which the molten metal is carried from the blast-furnace. *i i* are rail-tracks running under the converters, for carrying away the slag and for carrying the ladles and converter-bottoms into the repairing-house on track *j*. *K* is the railway, on which the slag-cars are transported from the blast-furnace; *M*, the steam-boilers for generating steam by means of the waste heat of the blast-furnace slag. *N* is a store-house. *O* is the table on which the ingot and metal are moved to and from the rolls. *P P* are the steam-pipes. *Q* are the engines for driving the blooming-mill. *R* is the blooming-rolls. *S* is the shears for trimming the bad end off the bloom. *T* are the engines for roughing. *U* is the roughing-rolls. *X X* are the points where the Figs. 1, 2, and 3 join each other.

Fig. 3: *V* is the foundry, and *V'* is the machine-shop building. *Y* are the engines for driving the rail-finishing rolls *Z*. *o o o o* are saws driven by shaft *p*. *q* are steam-boilers for generating steam by the heat radiated from the rails while cooling.

In the practice of this invention by the use of a plant such as shown in Figs. 1, 2, and 3 of the drawings, the iron ores, coke, and limestone are run into the stock-houses *L* by means of tracks *r, s, t*, and *u*. The stock is then filled into wheelbarrows and raised to the top of the furnace by means of the hoist *D*. It is wheeled from the hoist over the bridge *E* and put into the tunnel-head. Each of the furnaces is provided with three hot-blast stoves and a battery of steam-boilers. When the fire is lighted the blast is let on, and as the top of the furnace is closed with a ball and hopper the gases are forced into the regenerating hot-blast stoves and under the steam-boilers. The gas passes from the boilers into the stack *C*. The gas which passes through the regenerators heats up the brick-work of the stove and passes off into stack *C*. When one of the regenerators has become hot the gas is excluded from it and caused to flow through the other two regenerators, and the cold air is forced through the hot regenerator and from thence through the tuyeres into the furnace. In about two hours the valves are reversed and the gas is caused to flow through the regenerator which the air had passed through, and the air made to pass through one of the hot regenerators. Thus two of the regenerators are being constantly heated by the waste gases while the air is being heated in passing through one of the hot regenerators. By this means the air may be heated to 1,500° Fahrenheit and the temperature of the gases entering the stack *C* reduced to 500°.

When the furnaces are in good working order a sufficient amount of steam will be gen-

erated from the waste gases to run the blowing-engines $h h h h h h h$ (shown in Fig. 2) to supply sufficient blast to blow the four blast-furnaces and the three converters $a a$. When the slag begins to flow from the blast-furnace it is caused to run into a slag-car, H . As soon as one of these cars is filled at each furnace the four slag-cars are taken by an engine and run into the steam-boiler M , the doors are closed, and fresh cars run up to the furnace. This hot slag will give off its heat and vaporize the water, and thus steam will be generated every two hours. Another batch of hot slag-cars are pushed into the boilers and the cooled cars are pushed out. By this arrangement of generating steam by means of the waste heat of blast-furnace slag I am able to produce sufficient steam for four thousand horse-power from a plant of this size.

When the metal is ready for tapping ten tons of the molten iron is caused to flow into car I . The car is then run onto the scale J^2 and weighed. The car is then taken up to the converters and the metal emptied into the converter. The converter is then turned up and the metal blown with an air-blast until the silicon and carbon are eliminated. The converter is then turned down and the metal de-oxygenized and re-carburized in the usual manner. The metal is then poured into ingots, and this operation continued by bringing another charge of metal from the blast-furnace. Immediately after the metal has been cast into ingots the molds are removed and the ingots taken, one at a time, and dropped into the ingot regenerator-hopper f . Each time an ingot is dropped in it is pushed forward one length of itself by means of the ram g . This is continued until the ingots appear at the other end of the regenerator. When the ingots are placed in the regenerator (which has been previously heated) the insides of the ingots are in a molten state, and the outsides are too cold for rolling; but by keeping the ingots in the hot regenerator for from twenty to thirty minutes the outside becomes hotter and the center solidifies, and a uniform and desirable temperature for rolling is secured without the use of fuel for reheating. When the ingots are thus prepared for rolling, an ingot is dropped into the hopper f and it is pushed forward by the ram g . In so doing every ingot in the regenerator is pushed forward, and thus an ingot is pushed out of the other end and onto the bloom-mill table. The ingot is then bloomed by means of rolls R . The fourteen-inch-square ingot is then reduced to a seven-inch-square bloom. This bloom is then run through the shears S and the bad end trimmed off. The bloom is then run forward and into roughing-rolls U , where it is roughed to the proper shape. The metal is then run forward and into the rail-rolls Z , and then rolled into the form of a rail, the rail being ninety-five feet long. It is run forward to the saws $o o o o$ and cut into three rails of thirty feet length. These rails are then bent in the usual manner, and

then pushed into the rail-receiving boiler q at the end m , and by continuing to push fresh hot rails into the boiler it becomes filled. The heat of the rails, while cooling, vaporizes the water, and a large amount of steam is then generated. This rail-receiving boiler is a flat structure having an internal flue of about thirty-one feet wide and six inches high, with an outer shell of such dimension as to leave a water-space of three inches on the bottom and sides and six inches on the top. It is also provided with a steam-drum, safety-valve, and supply-pipe. It is also provided with swinging doors at each end, so arranged as to be automatic—to open when the rail is pushed in at one end and pushed out at the other end, and shut when the operation is performed. The boilers should be about one hundred feet long when single rails are rolled and about one hundred and fifty feet long when three-length rails are rolled. When the rail-receiving boiler is filled and a hot rail is pushed in at m a cooled rail will be pushed out at the other end, n . The cool rails are then taken to the press, straightened, and drilled in the usual manner. At the end of the turn the rails may be allowed to remain in the boiler, and when hot rails are pushed in the cold rails will be warmed sufficiently for straightening; or the rails may be drawn out by means of suitable machinery.

By the practice of this invention as described it will be noticed that no use is made of the casting-houses $G G G G$; but as it is considered a work of necessity to run the blast-furnaces every day, while the converting and finishing departments are only run six days in the week, the furnaces are each provided with a casting-house, so that the metal made on Sunday may be cast into pigs in the usual manner. The hot rails will be pushed into the boilers at a temperature of about $1,000^{\circ}$ Fahrenheit, and will pass out of the boilers at about 500° Fahrenheit, so that five hundred units of heat may thus be utilized from each pound, which will be sufficient to vaporize steam for one horse-power from fifty pounds of rail, with ample allowance for loss of heat by radiation.

A plant of the capacity described will produce six hundred net tons of rails per day, and generate sufficient steam in cooling to furnish one thousand horse-power per day of twenty-four hours.

By the practice of this invention iron and steel may be manufactured direct from the ore without the use of any other fuel except that used in the blast-furnace, and sufficient steam generated from the cooling slag and metal to propel all the machinery required in manipulating the metal into all the forms desirable. The switching-locomotives may even be supplied with steam from slag-cars, so as to dispense with the use of fuel for locomotive purposes.

The advantage of this invention is that it saves the fuel and loss of iron in melting, which amounts to about one dollar and a half

per ton. It saves the cost of fuel and waste of iron in reheating the ingots and blooms, which amounts to about two dollars per ton. It saves the labor of melting and reheating, which will 5 amount to fully fifty cents per ton, which, together with saving of repairs and cracked rails caused by burning and careless heating, will amount to fully five dollars per ton on the amount of rails produced.

10. What I claim, and wish to secure by Letters Patent, is—

1. The method herein described of producing blooms directly from the ore, consisting in the following consecutive steps: first, conveying 15 the molten metal directly from the blast-furnace to the converter and the waste gases into and through the blast-ovens; secondly, casting the converter-metal into ingots and passing the same, while the center remains 20 molten, through a soaking-chamber or regenerator to the roughing and blooming rolls; thirdly, subjecting them to the action of the blooming-rolls, and conveying the hot slag from the furnace to the boilers for supplying 25 steam for driving said rolls, whereby the intermediate heating and steam-generating furnaces are dispensed with, substantially as and for the purpose specified.

2. The method herein described of producing rails and like articles directly from the ore, consisting of the following consecutive steps: first, smelting the ore in a blast-furnace, conveying the molten metal therefrom directly to the converter and the waste gases 30 into and through the blast-ovens; secondly, casting the converter-metal into ingots and passing the same, while the center is molten, through a regenerator or soaking-chamber to the blooming-rolls, conveying the slag to the 35 boilers which supply steam to drive the rolls; and, finally, passing the ingot successively through the blooming and rail rolls, whereby the continuous working of the metal from the initial step of smelting to the finished rail is 40

attained without the usual intervening furnaces for reheating and for generating steam, substantially as and for the purpose specified. 45

3. A plant for producing blooms directly from the ore at a continuous operation, and with the initial heat of the smelting process, consisting of a blast furnace or furnaces and hot-blast ovens, a converter or converters and blowing-engines, a regenerator or soaking-chamber, blooming-rolls, and boiler and engine for operating the same, said several elements 50 relatively arranged as herein specified, and connected by suitable tracks and conduits, so that the waste gases will be conducted to the blast-ovens and the molten slag may be conveyed to the boilers, substantially as and 55 for the purpose specified.

4. A plant for producing rails, &c., directly from the ores without other heat than that evolved in the smelting process, consisting of a blast-furnace having suitable hot-blast ovens 60 and conduits for conveying the waste gases thereto, a converter or converters, a regenerator or ingot-soaking chamber, a blooming-mill, with boiler and engine for driving the same, tracks for conveying the hot slag to said 65 boiler, and a rail-mill with rail-receiving boiler and an engine, said elements relatively arranged as specified, and connected by tracks, substantially as and for the purpose specified. 70

5. The herein-described improvement in the 75 art of rolling ingots into two or more rail-lengths without reheating, which consists in cutting off the ragged end of the bloom which has been made from the top of the ingot before it passes into the rail-finishing rolls, whereby a 80 bloom with solid ends may be secured, the collars of the finishing-rolls preserved, and sound rails produced direct from the ingot, substantially as and for the purpose specified.
